Des. 178,696
Patented Sept. 4, 1956

178,696

AQUARIUM SHADOW BOX

Timothy T. Ross, Cleveland, Ohio

Application September 20, 1955, Serial No. 38,003

Term of patent 3½ years

(Cl. D29—20)

Fig. 3

Fig. 1

Fig. 2

Figure 1 is a front elevational view of an aquarium shadow box showing my new design;

Figure 2 is a top plan view thereof; and

Figure 3 is a side elevational view of the same.

I claim:

The ornamental design for an aquarium shadow box, as shown.
